BABY WALKER

William H. Reinholt, Irondequoit, N. Y.

Application June 12, 1940, Serial No. 340,084

9 Claims. (Cl. 155—23)

The object of this invention is to provide a baby walker having a chair or seat in which the child can sit, which allows the baby to stand or walk in safety, and the chair or seat is supported for movement in a path which is restricted to a circle by means of a floor anchor.

Another object of the invention is to provide a baby walker of the character above described, which embodies a floor anchor that has sufficient weight to hold itself in place on the floor and provide a fixed axis about which the chair or seat is movable, and by reason of its weight it holds itself in one place and eliminates the need of fastening the anchor to the floor or other support.

Another object of my invention is to provide a baby walker which is strong and light weight and simply constructed and of low cost to manufacture and can be easily collapsed or knocked down for the purpose of packing or shipment.

Another object of the invention is to provide a baby walker that is attached to the floor anchor by arms that can be readily detached from the floor anchor and folded against the body of the baby walker.

Another object of the invention is to provide the floor anchor with a bail by which it can be carried easily from place to place, and also with a rubber or nonslip base to keep floor anchor in one place.

Another object of the invention is to provide a baby walker with a removable fabric seat and back, for the purpose of laundering.

Another object of the invention is to provide a baby walker having two side members which are fastened together by U-shaped members.

Another object of the invention is to provide a baby walker which the baby cannot tip over in use.

These and other objects of the invention will be shown in the drawings, described in the specification and pointed out in the claims.

In the drawings:

Figure 1 is a top plan view of my improved baby walker.

Figure 2 is a front elevation of the baby walker shown in Figure 1.

Figure 3 is a section on the line 3x—3x of Figure 2, looking to the right, the fabric seat being removed.

Figure 4 is a detail view of the U-shaped frame that supports two sides and front of the fabric seat.

Figure 5 is a perspective view of a modified form of the baby walker.

Figure 5a shows a cross section of the channel on the line 5x—5x of Figure 5.

Figure 6 is an enlarged detail view of the U-shaped frame that supports two sides and front of the fabric seat, with the supports therefor partly broken away, the frame and supports being looked at from below in Figure 5.

Figure 7 is a sectional view through the anchor, one-half of part of the anchor being omitted, the parts being enlarged.

Figure 8 is a perspective view of the frame of the baby walker partly broken away and showing a U-shaped frame that is a modified form of that shown in Figure 6.

Figure 9 is a perspective view of a modified form of frame for a baby walker.

Figure 10 is a detail view of a joint in the frame, the rest of the frame being broken away.

Figure 11 is a detail view of a portion of the upright frame and the U-shaped frame that connects therewith, the parts being held together in one direction by a thumb nut.

Figure 12 is a sectional view of the baby walker corresponding to Figure 3, but showing a modified form of the side frame and parts associated therewith.

Figure 13 is a section on the line 13x—13x of Figure 12.

In the drawings like reference numerals indicate like parts.

In the drawings reference numeral 1 indicates one upright side member of the baby-go-round and 2 indicates the other upright side member. Fastened to the top of each side member is a horizontal rail 3 and 4. At the forward lower end a U-shaped member 5 is provided, the short parallel horizontal ends of which engage in the horizontal sockets 6 and 7. A similar U-shaped member 8 is provided at the back, the short sides of which engage in sockets 9 and 10 on the side members. By these U-shaped members 5 and 8 the side members are held suitably spaced apart at the bottom. The intermediate parts of these U-shaped members are preferably covered with rubber tubing so that they can serve as bumpers. The sockets 6 and 7 are formed of a single plate 11, the intermediate part of which is bent to form an upright socket 12 which holds the stem of the caster 13 and is swiveled therein. This is also true of the plate 14, in which the sockets 9 and 10 are formed. One of these plates with the three sockets therein is in each lower corner of the baby-go-round, and at each of these lower corners the caster wheel

40

45

50

55

is swiveled therein, four caster wheels being provided on the baby-go-round.

The horizontal rails 3 and 4 are perforated with holes as indicated at 15 at the back and 16 at the front. The holes 15 are inclined, for a purpose that will presently be described, and the holes 16 are upright. Through the holes 15 is inserted a U-shaped frame 17, which frame extends through sockets formed in the plates 18 and 19, which plates are riveted to the side members for the purpose of completing the sockets and holding the plates in place. At the lower end of the socket in the plate 18 the metal is spun inwardly to form a flange or bottom to limit the downward movement of the member 17. A plate and socket similar to the part 18 is provided at 20 and a U-shaped member 21 is provided, the sides of which extend down through the holes 16 in the rails and the ends of which engage in the sockets in the plate 20.

As shown in Figure 3, the U-shaped member 17 is held in upright inclined position and the U-shaped member 21 is held in an upright vertical position.

In Figure 4 I have shown the U-shaped member 22 which is supported from the sides 1 and 2, and which in turn supports three sides of the fabric seat member. This member is supported by two cleats or brackets 23 and 24 on each of the side members 1 and 2. The ends of the U-shaped member 22 taper toward each other and must be sprung out to engage with the cleat 23, and the ends of the side members are bent down as indicated at 25 to hold the member 22 positively in its proper position.

The sides of the member 22 are bowed inwardly, as indicated at 26 to pass around the upright sides of the U-shaped member 21, and they are also bowed down and inwardly at 27 to form suitable supports and sockets for the ends of the cross bar 28, on which the forward end of the fabric of the seat is supported.

The fabric of the seat has a sleeve on each side thereof which engages with the sides of the member 22. It has a sleeve formed at the front which engages over the cross bar 28 and the fabric extends forward and has another sleeve formed on the end thereof that engages over the intermediate part of the U-shaped member 22. The fabric between the bar 28 and the intermediate part of the U-shaped member 22 forms a tray in which the baby's food or toys can be held. At the back the fabric is formed with a pocket 30, which engages over the U-shaped member 17, by which engagement the rear portion of the seat is supported.

Inside of the member 2 is attached four plates, 31, 31 having sockets therein in which are mounted to swing the upright members 32 of the radial arms 33. These upright members are turned over at the top so that they will remain engaged with and be supported by the top sockets 31. The arms 33 are free to swing to the position shown in Figure 1, or they can be folded against the side member 2. The outer ends of the arms 33 are bent down and then out, so as to form a suitable engagement with the undercut socket 34 in the floor anchor 35, in which they can swing freely as the wheeled chair circulates around the floor anchor.

As shown in Figure 7, this floor anchor is preferably made with a metal socket or housing, which is surrounded by a disc of concrete 35a. On the bottom of this disc is a plate 36 of rub-

ber, which has more or less adhesion to the floor that will hold it from sliding on the floor. On the floor anchor is provided a bail 37, by which the floor anchor can be easily lifted and moved from place to place. The arms 33 are engaged with the floor anchor by tilting either the baby-go-round or the floor anchor, and when the parts are in the position shown in Figure 1 the upright members 32 with their positive engagement in the side member 2 holds the baby-go-round from tipping over sideways. The baby-go-round and its floor anchor described above is substantially the same as that shown in Figure 9 of my co-pending application 275,031, filed May 22, 1939, which issued as Patent No. 2,308,626 on Jan. 19, 1943, to which reference is made.

On the U-shaped member 21 a cross bar 38 is supported on which beads and bells 39 can be mounted to slide and swing.

In Figure 5 I have shown a modification of this structure in which is provided the side bars 40, 41 to the ends of which are fastened the C-shaped members 42, 43, which members are channel-shaped in cross-section, as shown in Figure 5a.

The bar 40 and the C-shaped member 42 constitutes one side member of this form of baby-go-round, and the bar 41 and the C-shaped member 43 constitutes the other side member of this form of baby-go-round. These side members are held together at the front by a U-shaped member 44, and at the back by a U-shaped member 45, which members are the same as the members 5 and 8 shown in Figure 1. The sides of each of these U-shaped members 44 and 45 pass through holes in the C-shaped members 42 and 43 and positively engage in suitable sockets provided in the ends of the bars 40 and 41. In this way the two side members are held together and spaced apart at the front and back.

Each of the C-shaped members are perforated near the top as indicated at 46 and 47, and the bars 40 and 41 are also provided with inclined sockets in line with such perforations. The U-shaped member 48, corresponding to the member 21 in Figure 3, is inserted through the holes 46 and engages with the inclined sockets 49 in the bars 40 and 41. The U-shaped member 50, corresponding to the U-shaped member 17 passes through holes 41 in the C-shaped members and engages with the inclined sockets 51 in the bars 40 and 41. In this way the two side members are suitably spaced apart and held together at the top by the U-shaped members 48 and 50.

Between the upper portions of the C-shaped members the U-shaped frame 52 is supported, the sides of which engage positively in and are supported by the channels of the C-shaped members, and the intermediate part of which forms a cross bar that extends across between the two C-shaped members. Shoulders 52a and 52b are formed or bent on the sides of the frame 52 for engagement with the edges of the channels. The sides of the frame 52 normally stand in the dotted line positions shown in Figure 6, and to be engaged with the channels in the C-shaped members 42 and 43 they must be spread out or sprung to the full line position shown in Figure 6, after which they can be forced into engagement with the channels, with which they will positively engage. The fabric seat is provided with a sleeve at the front and on the two sides, which engage with and is supported by the U-

shaped frame 52. The rear of the fabric seat is formed with a pocket, which engages over the upper end of the U-shaped member 50, similar to the arrangement shown in Figures 1 and 2.

A cross bar 54 is provided on which bells and beads may be hung. Arms 33a are provided with an eye on the end thereof. Screws pass through these eyes up into the bar 40, on which screws the arms 33a can swing. The outer ends of the arms 33a are bent down and out as shown in Figure 7 to engage the anchor 35.

In Figure 8 I have provided a U-shaped frame 60, which is a modification of that shown in Figure 6, in which the frame is formed on one piece of wire and is bent to form eyes 61, 62, 63, and 64 at the four corners thereof, which eyes engage the U-shaped members 48 and 50, it being understood that the U-shaped members 50 and 48 pass through these eyes and then into the side frame, just as they do in Figure 5.

In Figure 9 I have shown a modification of the frame of the baby-go-round in which the frame comprises the forward U-shaped member 70 and the back U-shaped member 71 both of which are bent to shape shown in Figure 9. These members are formed of pipe or tubes and where the members come together as indicated at 72-72 the pipes are flattened and are perforated, and are held together by bolts 73. The frames 70 and 71 are also perforated to receive the U-shaped member 74 which passes through them and connects them. The rear ends of the member 74 are threaded and are held in place by the thumb nut 75. The U-shaped member 74 is used to support two sides and the front of the fabric seat and the back of the fabric seat is supported by frame 71. Four caster wheels and their sockets are inserted in the lower ends of the members 70 and 71. Anchor arms 33b are provided which arms have eyes at one end thereof and engaged on one side of the frame, the other end of these arms engaging in the anchor shown in Figure 7.

In Figure 12 I have shown another modification of the baby-go-round in which each of the side members 80 are stamped out of a single metal sheet, the outer edge of which is spun over to form a flange 81 and at suitable places sockets 82, 83, 84 and 85 are formed to receive the U-shaped members 17a and 21a and sockets 86 and 87 are formed to receive the arms 33. Upright sockets are also formed to receive the stems of the casters and the bottom flange is also perforated to receive the stems of the casters. Sockets 88 and 89 are formed to receive the ends of the U-shaped members of 5 and 8, and the flange 81 is perforated to permit the U-shaped members 5, 8, 17a and 21a to pass through for the purpose of engaging with the sockets. A U-shaped frame 60a is provided with eyes at the corners thereof which is substantially the same as in the frame 60 shown in Figure 8. This frame has eyes at the corners thereof which rest on top of the sockets 82 and 84 and through which pass the U-shaped members 17a and 21a. The fabric seat is held by the U-shaped frame 60a and the U-shaped member 17a substantially as is shown in Figure 8.

I claim:

1. In a vehicle of the character described, the combination of two upright frame members suitably spaced apart, horizontal sockets in each end of said upright members near the bottom thereof, a U-shaped member engaging with said sockets in the upright members both from the front

and the back for the purpose of holding them together and suitably spaced apart, upright sockets provided in the upright members at the top and bottom thereof, a U-shaped member engaging in said sockets of the upright members for holding them together and suitably spaced apart.

2. A baby walker of the character described, comprising two side frames each having horizontal sockets at the front and back thereof near the bottom and arranged in pairs, each of said frames having an upright socket therein; a U-shaped member at the front engaging one pair of the lower horizontal sockets, and a U-shaped member at the back engaging the other pair of the lower horizontal sockets, and an upright U-shaped member engaging the upright sockets in the two frames, said U-shaped members holding the side frames together and suitably spaced apart.

3. In a vehicle of the character described, the combination of: a pair of uprightly disposed, horizontally spaced side frame members; a horizontally disposed cross bar connecting the lower front portions of said side frame members and projecting forwardly in advance thereof; a horizontally disposed cross bar connecting the lower rear portions of said side frame members and projecting to the rear thereof; a cross bar connecting the upper portions of said side frame members; a child's seat carried by and between said side frame members, the space between said side frame members, floor, seat, and lower cross bars being free and unobstructed; supporting wheels carried by each of said side frame members at the forward and rear ends, respectively, thereof; a pair of links, one of said links being connected to one of said side frame members adjacent the forward wheel thereof and the other link being connected to one of said side frame members adjacent the rear wheel thereof; and a movable floor anchor having an upright socket therein, said links extending from said one of said side frames convergingly toward said floor anchor and engaging with said socket.

4. A vehicle of the character described, comprising a frame, said frame comprising two upright side members suitably connected by cross bars at the bottom at both the front and the back and by a cross bar at the top, wheels supporting said frame, links connected to one side of said frame, wheels under said frame both at the forward end and at the rear end, one of said links being connected with the frame near the forward wheel on one side and the other of said links being connected with the frame near the rear wheel on the same side, a floor anchor having an upright hole therein, said links converging to and engaging with the hole in said floor anchor, the links being mounted so that they can be detached from the floor anchor and being pivotally connected to the frame on one side so they can be folded against that side.

5. A vehicle of the character described, comprising a frame, said frame comprising two upright side members suitably connected by cross bars at the bottom at both the front and the back and by a cross bar at the top, wheels supporting said frame, links connected to one side of said frame, wheels under said frame both at the forward end and at the rear end, one of said links being connected with the frame near the forward wheel on one side and the other of said links being connected with the frame near the rear wheel on the same side, a floor anchor having an

upright hole therein, said links converging to and engaging with the hole in said floor anchor, said hole in the floor anchor being undercut, the ends of said links being bent down and out to positively engage in said undercut hole and rotate therein.

6. In combination: a wheeled baby walker; a movable floor anchor having an upwardly opening, centrally disposed socket formed therein; and a link means projecting from one side of said walker and having its outer end projecting downwardly into said socket to form a readily disengageable connection therewith, and adapted when connected to said anchor to limit the movement of said baby walker to a circular path about said anchor as a center, said link means being retractable to a nonprojecting position on the walker and securable in said position.

7. The combination defined in claim 6 in which said anchor is provided with a friction base and a ball pivotally connected to said floor anchor above the center of gravity thereof.

8. In a baby walker, the combination of: a pair of parallel, upright, horizontally spaced side members; caster wheel means supporting each of said side members; a horizontally disposed cross bar connecting in a readily disengageable manner the lower forward portions of said side

members; a horizontally disposed cross bar connecting in a readily disengageable manner the rear lower portions of said side members; a cross frame means connecting in a readily disengageable manner the upper portions of said side members; a fabric seat suitably mounted on said frame means, the space between said side members, said frame structure, said horizontal cross bars, and the floor being free and unobstructed and said cross bars being longitudinally spaced to accommodate the walking movements of the legs of a child seated in the fabric seat; and means for readily disengageably connecting one of said side members to a floor anchor for limiting movement of the walker in a circular path about the floor anchor.

9. In a baby walker, the combination of: two parallel upright panels of sheet metal; socket means having their axes parallel to the planes of said panels and formed by being stamped therein; a plurality of U-shaped cross members, each having a cross bar and end legs normally disposed to said cross bar, said U-shaped members and socket means being adapted for engagement to hold said panels in parallel spaced relationship; a seat carried between said panels; and wheeled means for supporting said panels.

WILLIAM H. REINHOLZ.
